UNITED STATES PATENT OFFICE.

CHARLES H. WELLS, OF ENDICOTT, NEBRASKA.

STOCK-CAR PARTITION.

Application filed July 10, 1926. Serial No. 121,607.

My invention relates to stock car partitions, it being my object to provide a partition which is simple in construction, which is suspended so that it may easily be manipulated and shifted to any part of the car to control the movements of the animals during loading and unloading, and which may be firmly secured in place to divide the car into compartments for keeping the various groups of animals separate during transportation.

Having in view these objects and others which will be pointed out in the following description, I will now refer to the drawings, in which

Figure 1 is a view in perspective of the interior of a stock car and showing also the stock car partition and its track.

Figure 2 is a transverse sectional view of the stock car showing the stock car partition in its latched position.

Figure 3 is a view in perspective showing a detail of the track and its hanger, a portion of the track being broken away to disclose the runners.

Figure 4 is an illustration of the stock car equipped with my stock car partition and with a special form of bullboard or apron and showing the manner in which such car is loaded.

Figure 5 is a plan view of the interior of a stock car with the bullboard or apron in place between the stock car and the truck and with a partition for controlling the movement of the stock toward one end of the car.

Figure 6 is a similar view showing the partition shifted to confine the stock which was first loaded and to guide the movements of stock toward the other end of the car.

Figure 7 is a similar view showing the use of three partitions to form four compartments in the car, three of which are shown as loaded.

Figure 8 is a side elevation of the car, the arrangement of partitions being the same as that shown in Figure 7.

The partition itself is best shown in Figures 1 and 2. It consists of alternate series 50 of slats 10 and 11, the slats 10 being all secured together in parallel relation by means of the straps 12 at their opposite ends. The slats 11 are positioned between the slats 10 and are slideable in and out in the direction 55 of their length. In order to cause simultaneous movement of the slats 11 they are

connected at their inner ends by means of the straps 13.

The straps 12 project upwardly to some distance above the upper slat 10 and they are 60 connected at their upper ends by the beam 14. Secured to the beam 14 are links or chains 15, preferably three in number, these links being connected at their upper ends with the eye 16 of the hanger. The eye bolt 16 is in 65 turn connected to the hanger 17 so as to swivel thereon. The hanger 17 has the form shown in Figure 3 with its upper end portion vertical and having a pair of rollers 18 journaled on the upper end portion of the 70 hanger and on the two sides thereof. The track 19 is similar to that frequently used for hanging sliding barn doors and the like and it consists of a hollow tubular portion having a longitudinal slit at its lower side. This 75 slit receives the upper end portion of the hanger 17, and the inwardly projecting flanges on the lower side of the track 19 serve as tracks for the rollers 18. The track 19 is secured to the ceiling of the stock car 80 and is so designed that it may be secured by means of the bolt arrangement already found in all stock cars. This is done to avoid the necessity of providing additional bolt holes for the hangers and thereby possibly weakening 85 the construction of the stock car. The vertical dimensions of the various parts are such that the partition will have a slight clearance between its lower edge and the floor of the stock car so that it may be 90 readily moved about from place to place in the stock car along the track 19. The upper edge of the partition is on a level with the lower edge of the manhole in the end of the car.

Stock cars are provided with uprights 20 of rather heavy construction and I make use of these in applying my stock car partition to the car. Adjacent but spaced from each upright 20 I secure an additional upright 100 21 as shown in Figures 4 and 8. The uprights 20 and 21 are spaced a distance equal to the thickness of the slats 11 of the partition. The partition may thus be latched between the uprights 20 and 21 by simply 105 moving the slats 11 outwardly until they project between the slats 20 and 21 to prevent movement of the partition. I find it best to additionally provide a metal strap 22 or the like between the uprights 20 and 21, 110 the straps 22 serving as abutments for the outer ends of the slats 11. The parts are

firmly latched in position and the accidental unlatching is practically impossible because of the friction between the slats 10 and 11, but in order to prevent any possibility of accidental unlatching I provide pins 23 slidably secured in the upper slat 10 of the partition, these pins being secured by means of flexible elements 24 connecting the upper ends of the pins 23 to the beam 14. When the slats 11 are in the position shown in Figure 2, the pins 23 serve as abutments to prevent the inward movement of the slats but when the slats 11 are in the position shown in Figure 1, the lower extremities of the pins 23 merely rest on the upper edge of the topmost slat 11 and permit the outward movement thereof.

The bullboard or apron 25 as shown in Figures 4, 5, 6 and 7 is another important feature. The prior practice involves the laying of planks between the truck and the stock car, the planks serving as a bridge over which the stock must pass. The bridge is, of course, insecure because it is unattached but it involves serious difficulties when closing the door of the stock car. After the bridge is removed and before the sliding door has been closed the crowding of the cattle in the car frequently forces some of the animals to the door with the result that they are apt to break their legs or to be otherwise seriously injured. In order to overcome this difficulty I hinge the bullboard 25 to the floor of the car in such a manner that it may lie flat on the floor of the car or that it may be swung around through three quadrants until it is suspended perpendicularly on the outside of the car. Being secured to the car floor there can be no danger whatever of its being displaced by the shuffling of the cattle. When the car has been loaded the bullboard or apron 25 is lifted to its upright position while the sliding door is closed to thus serve as a temporary closure.

The partition in particular has a number of uses especially in connection with stock cars. It is, of course, very important in cutting out and dividing the cattle in the manner shown in Figures 5 and 6. It is also very important for dividing the stock in the car. Mixed shipments of the various animals do not, of course, travel well together and the freight rates are necessarily high on such shipments. Such mixed shipments are also liable to suffer serious injury which could be prevented by segregating the animals of the various groups in the manner shown in Figures 7 and 8. This is true not only when animals of several species are loaded but it is equally true when the shipment contains one or more vicious animals which are liable to seriously injure the others.

Shipments of stock at the present time are

confined in improvised compartments of the stock car, the partitions being made of beams and planks which are spiked to the frame of the car. The use of these beams necessarily involves a heavy waste of labor both in segregating the various groups of animals and in securing the beams in place. These beams cause further trouble and loss of time when unloading the shipment. The beams moreover are usually so badly split by the spikes that they are seldom in condition to be used a second time, thus resulting in a serious waste of material. The work is apt to be done hastily with spikes left protruding in the car and with the wood of the car badly split so that it is usually found that the car is badly in need of repairs after it has been once loaded and unloaded. If any of the protruding spikes are accidentally left, the next shipment of cattle is very liable to be injured, thus causing further loss to the railroad company in damages. All of these objections are eliminated by the use of my stock car partition.

While my invention is designed primarily for use for segregating groups of animals in stock cars, it is useful also for dividing shipments of other forms of freight. With slight modifications it may be used not only in freight cars but also as partitions in trucks and in ships to form temporary compartments for compactly holding various kinds of matter and articles which are to be transported. The partition will also be found to be useful in stock yards and on stock farms since it affords a convenient device for dividing a pen into small or large compartments when it is desired to keep some of the animals separate from the rest for special treatment or rations.

Having thus described my invention in such full, clear and exact terms that its construction and utility will be readily understood by others skilled in the art to which it pertains, what I claim as new and desire to secure by Letters Patent of the United States is:—

1. A stock car having lateral walls consisting of a plurality of pairs of spaced uprights and horizontal beams connecting said uprights and secured thereto in spaced apart relation, a portable partition in said stock car, said partition including horizontal fixed beams having a length slightly less than the inner width of the car, said fixed beams being secured together in parallel and spaced apart relation, slidable beams between said fixed beams, said slidable beams being each formed of two oppositely slidable parts, a pair of straps connecting said slidable beams whereby all of said slidable beams will be in two oppositely movable groups so that their extremities will enter the rectangular spaces between the uprights and the horizontal beams of the stock

car, and straps between each pair of said uprights for limiting the outward movements of said slidable beams.

2. A stock car partition including a plurality of beams which are secured together in parallel and spaced apart relation, a plurality of slidable beams between said first named beams, said slidable beams being each formed of two parts which are each slidable outwardly, straps connecting all of said parts on one side of the median line of said partition whereby said parts on either side of the median line may be slidably moved as a unit, means adapted to be secured to the frame of the stock car for limiting the outward sliding movement of said slidable beams, a pin which is adapted to pass through one of said first named beams to function as an abutment for the inner extremity of one of said slidable beams for preventing the inward movement of said slidable beams, and means for slidably suspending said stock car partition in a stock car.
- 25 3. A stock car partition including a plurality of horizontally positioned beams in vertical and spaced apart relation, a pair of straps connecting said beams together, said

straps projecting above the topmost beam and being connected at their upper extremity by a supporting beam, slidable beams positioned between said first named beams, said slidable beams being each formed in two parts which are slidable in opposite directions, a pair of straps each connecting the parts of all of said slidable beams on the same side of the median line of the partition, said first named straps serving as guides for the movements of the parts of said slidable beams, an abutment which is adapted to be secured to the frame of the stock car for limiting the outward movement of said slidable beams, pins suspended from said supporting beam, said pins being adapted to pass through the uppermost of said first named beams to serve as abutments to prevent the accidental inward movement of said slidable beams, a plurality of links secured to said supporting beam, the said links being connected at their upper extremities to a hanger, and a track for said hanger, said track being adapted to be secured to the ceiling of the stock car in lengthwise position therewith.

In testimony whereof I affix my signature.
CHARLES H. WELLS.
